CIGARETTE DISPENSING MACHINE

Donald Bruce Lane, Glen Cove, N. Y., assignor
to Kimmelman & Lane Holding Co., Inc., New
York, N. Y., a corporation of New York

Application October 3, 1931, Serial No. 566,674
Renewed May 16, 1935

5 Claims. (Cl. 312—86)

This invention relates to a device for dispensing lighted cigarettes or cigars, and more particularly to that type which is coin controlled. That is to say that type wherein the buyer brings about the setting in motion of revoluble parts which convey a cigarette from a reservoir to a dispensing tray causing it to pause long enough en route to be lighted.

The objects of the invention are to devise a dispensing apparatus of this type which is compact so that it can be housed in a relatively small and attractive casing; which is dependable in operation as all automatic vending machines must be to be successful; which is reasonable as to cost of manufacture; which will light the cigarette with a minimum of pausing adjacent the igniting element; which will deliver the lighted cigarette with its mouth-engaging end free from dirt and ashes; and which will assure the lighted cigarette continuing to turn after it has been delivered to the dispensing tray. Other objects also have been contemplated which will appear hereinafter.

The objects of this invention may be attained by a device set in functioning condition by the insertion of a coin which starts a motor operating to convey a cigarette from a hopper to a dispensing tray, causing it to pause en route when adjacent an electrical lighting element meanwhile causing suction through the cigarette to facilitate its being lighted. And then delivering the lighted cigarette to its dispensing tray in such a manner that it is free from ashes and that its continued burning is assured until picked up by its buyer.

Drawings accompany this specification for the purpose of illustrating one embodiment of my invention so that its nature may be readily understood. In these drawings Figure 1 is a vertical sectional view taken through my cigarette dispensing machine from front to back. Fig. 2 is a vertical sectional view taken along the line 2—2 in Fig. 1. Fig. 3 is a transverse horizontal sectional view taken along line 3—3 in Fig. 1. Fig. 4 is a partial view of the igniting element in vertical section along the line 4—4 in Fig. 3. Fig. 5 is a composite view showing diagrammatically the electrical circuit and a perspective view isolating the more important elements operated by the circuit.

This invention involves primarily the arrangement shown in Fig. 5. When this is understood, its embodiment in a machine is readily made clear, so a description of this arrangement will be given first.

In general, a coin inserted in a slot causes operation of a motor which rotates conveying means for conducting a cigarette from a reservoir to a dispensing tray but causing the cigarette to pause en route when its end is aligned with an igniting element (also energized by the motor operating circuit) long enough to be lighted thereby.

11 indicates a coin chute in an auxiliary electric circuit 12 so arranged that a coin in sliding down the chute closes the circuit, or rather it closes the circuit to a magnetic switch or relay 13 (having a spring pulled interrupter 14) which when once closed completes a circuit 15 and this circuit is maintained closed even though the circuit 12 is opened as soon as the coin slides out of the chute 11.

The main electrical circuit 15 includes a motor 16 which by suitable gearing rotates a commutator 17, a cigarette conveying drum 18, and an endless band 19 which conducts a cigarette from the cigarette reservoir to the drum conveyor 18. Laterally adjacent the drum conveyor 18, is the electrically operated cigarette igniter element 20 also in circuit 15. Therefore, closing of the circuit 15, energizes the motor 16 which rotates commutator 17, cigarette conveyor 19, and drum conveyor 18. A cigarette is delivered to the groove or recess 21 of drum 18, and the rotation of the drum 18 continues until it reaches a point adjacent to the igniter 20, the drum 18 pauses by means of interruptions on the drum driving gear (not shown in this figure but as 40 in Fig. 1). This pause is only long enough to cause ignition of the cigarette which is stimulated by an air suction operating upon the other end of the cigarette (described hereinafter). The igniter 20 is caused to glow at the proper time because it is in the same circuit 15 as the motor and is therefore concurrently operated. After pausing to permit lighting of the cigarette, the drum driving gear (40) is rotated again by its meshing interrupted gear 41 to discharge the lighted cigarette to the dispensing tray.

Upon discharge of the lighted cigarette, rotation of the commutator 17 has brought the insulation 23 in contact with brush 24 which breaks circuit 15, whereupon the spring pulled interrupter 14 is moved to still further break the circuit 15 and all parts are then ready for reoperation due to a coin passing through chute 11. Momentum of the motor causes continued rotation of commutator 17 until insulation 23 (after causing breaking of the circuit) passes by the brush whereby the brush is left in contact with

the "live" part of the commutator and is ready for re-operation.

Bearing in mind this principle of operation, the following structural arrangement will be understood.

The coin chute 11 is supported from the main casing 25 of my dispensing device, and comprises two spaced apart channel members 26 and 27, to each of which is attached a wire 28 and 29 respectively, forming a part of auxiliary circuit 12 as described in connection with Fig. 5. When a coin is slid down the chute 11, it bridges the space between the channel members 26 and 27 and completes the auxiliary electrical circuit 12 thereacross. Coins, after sliding down the chute 11, drop into a coin box 30 detachably supported upon a door 31 at the side of casing 25.

The cigarettes to be dispensed are stored in a reservoir or supply hopper 32, having an inclined bottom 33 terminating in a discharge passage or throat 34 whose cross-sectional area is only slightly larger than a cigarette from the hopper 32. There is a tendency for the cigarettes to become disarranged, so to rearrange the cigarettes to prevent their jamming in entering discharge passage 34 whose dimensions are such that only one cigarette can enter at a time, there is provided an endless band, conveyor or other impeller 19 moving upwardly within the hopper 32 whereby cigarettes on the inclined hopper bottom 33 are circulated upwardly therealong, over, and then down the throat 34. Conveyor 19 takes around an idler pulley 35 journaled in partition walls 36 and 37 in the casing 25. Conveyor 19 also takes around pulley 38 which is rotated by gear 39, driven through a train of gearing (to be described later on) by motor 16.

From the discharge passage 34, a cigarette drops into a recess 21 in drum conveyor 18 so that it may be conveyed by the drum as the drum is rotated. Rotation of the drum 18 is brought about by means of a gear 40, with which meshes an interrupted or mutilated gear 41 mounted on shaft 42. Shaft 42 is rotated by motor 16 through gear arrangement 43 (cooperating with motor shaft 57) vertical shaft 44 and worm gears 45. Vertical shaft 44 is suitably supported by brackets 46 mounted on partition 36. On shaft 42 is also mounted commutator 17 with its insulated block 23 and brush 24 operating in the main circuit 15.

Through the medium of the interrupted gear 41, when the drum conveyor with a cigarette in a recess 21 reaches a position in line horizontally with the igniter 20, the drum pauses. The igniter is mounted on partition wall 37 and comprises an electric glowable resistance element 47 held in place by screws 48 passing through a threaded plug 49 and a conductor plate to a knurled knob 51. The plug 49, by means of the knob 51 is screwable into and out of a socket 52 which contains electrical contacts 53 and 54 respectively in the circuit 15. From circuit 15, current is conveyed through contacts 53 and 54 to plate 50, and through screws 48 to the electrical glow igniting coils 47. The socket 52 is secured to partition wall 37 by means of screws 55.

While the conveyor drum 18 is at rest with its cigarette aligned with the igniter 20, suction is applied to that end of the cigarette opposite the igniter. Means for producing the suction comprises a fan member 56 on the motor shaft 57, in a housing 58, opening into which is a suction duct 59 leading from a point in the same horizontal plane as the igniter 20 but adjacent the

opposite end of the drum 18. The fan 56 sucks air through a cigarette in recess 21, and through duct 59, which air is expelled from the fan housing 58 through exhaust opening 60. The blades of the fan 56 stop short of the center of rotation 5 of the fan in order to leave an unobstructed space 61 for the thorough exhausting of the air sucked from or through the cigarette.

Renewed rotation of the drum 18 drops the lighted cigarette into the dispensing chute or tray 10 62. This tray is apertured at 63 to permit any dust or ash upon this end of the cigarette to fall through the tray and not to accumulate therein. Similarly, an aperture 64 is provided at the other end of the tray 62 so that sufficient air is 15 available to maintain the lighted cigarette burning until its purchaser can remove it from the tray 62. To facilitate the removal of the cigarette from the tray a recess 65 is provided to make easy the grasping of the cigarette by the buyer's 20 fingers.

During passage from the drum 18 to the tray 62 of the lighted cigarette, ashes may fall therefrom, so the tray 62 is apertured at 66. The bottom of the casing 25 is apertured with an aligned 25 opening at 66a to let the ashes fall therethrough. The back of the casing 25 is perforated at 67 to permit the exhaust from the fan housing 58 and exhaust opening 60 to pass out of the casing. A glass 68 is provided in the front of the casing 30 25 so the purchaser can see that there are still some cigarettes in the machine for dispensing. A door 69 is provided in partition 37 whereby a fresh supply of cigarettes can be placed in the hopper 32, and a further door 70 is provided in 35 the side of the casing 25 to give access to the mechanisms within the casing.

A gear 39 driving the conveyor 19 is driven from a gear 71 mounted on shaft 72 on which drum conveyor 18 is carried.

Operation.—The would-be cigarette buyer in approaching the machine would in all probability observe that there was present a vendable supply of cigarettes as they would be apparent through inspection glass 68. Then the buyer would insert 45 his coin in chute 11, the coin making electrical contact or connection between coin guides 26 and 27 and their wires 28 and 29 completing auxiliary circuit 12. Completion of this circuit 12 (see Fig. 5) by energizing electromagnet 73 causes depression of the interrupter 14 against the pulling of spring 74 against the interrupter. Depression of interrupter 14 closes the gap between interrupter and contact 75. Closing of the gap between interrupter and contact 75 closes circuit 15 which 55 is the main operating circuit. Closing of this circuit also energizes magnet 73 so the interrupter 14 is held closed even after auxiliary circuit 12 is broken by the coin dropping out of its chute.

The coin slides through the chute 11 so its 60 momentary completing of the auxiliary circuit 12 must be used to close main circuit 15 in a way which will maintain circuit 15 closed to bring about the required operation of the device.

So, closure of circuit 15 sets in operation motor 65 16 and this in turn operates three things, namely, the impeller or band 19 for rotating the body of cigarettes whereby cigarettes from the hopper 32 singly pass down through the throat passage to the drum conveyor 18; rotates drum 18 to take 70 from the throat one cigarette at a time and pausing when its cigarette is adjacent igniter 20, energizes igniter 20 to cause it to flow; operates fan 56 to cause a constant suction on the cigarette while being ignited; and rotates commutator 17 where- 75

by the motor circuit is broken after the motor has done its work.

Describing the operation of each of these phases in more detail—motor 16 rotates its shaft 57 which through the medium of gearing 43, vertical shaft 44 and gearing 45 rotates shaft 42. Rotation of shaft 42 turns interrupter gear 41 and this gear turns gear 40 and through it shaft 12 with the elements carried by it, conveyor drum 18 and gear 11. Gear 11 meshes with and turns gear 39. Rotation of gear 39 operates the endless belt 19 which orderly directs a cigarette from the hopper 32 down through throat passage 34 singly into a recess 21 on drum conveyor 18.

15 Rotation of drum 18 by the meshing of gears 40 and 41 carries the cigarette in its recess 21 until the non-toothed portion of the interrupted gear 41 comes around which is timed so that this happens just when the cigarette in its recess is aligned with and becomes adjacent to the igniter 20. Passage of the non-toothed portion of the gear 41 over the gear 40 permits the cigarette to pause adjacent the igniter long enough for it to become lighted. As the toothed portion of gear 25 41 comes in contact with the toothed gear 40, the drum 18 is rotated again and the lighted cigarette falls from its recess and down into the dispensing tray 62.

Retracing our steps to the closing of the main circuit 15, it will be seen that this also causes current to flow to the igniter through wires 53 and 54 and the coiled resistance element 47 to glow which is used to light the cigarette.

Again, operation of motor shaft 57 rotates fan 56 which causes suction through duct 59 and also through a cigarette on drum 18 when aligned with igniter 20 which assures lighting of the cigarette.

And finally, rotation of shaft 42 causes rotation 40 of commutator 17 until insulation block 23 comes in contact with brush 24 which breaks circuit 15. This in turn deenergizes magnet 73 and permits spring 74 to pull interrupter 14 away from contact 75, whereupon all parts are stopped and arranged for re-operation anew.

It will thus be seen that I have devised a cigarette dispensing machine with several outstanding advantages. One is the interposing of a throat between the cigarette reservoir or hopper and the rotating drum which conveys the cigarette past the igniter. This throat arrangement provides a minimum aperture for the delivery of one cigarette at a time to the feed mechanism so that the cigarettes in the hopper may be maintained under proper humidifying conditions. Another feature consists in the control of the cigarettes passing to the throat by setting up a mass rotation movement of the cigarettes in the hopper but in a manner which produce a minimum of tobacco crumbs. Another feature is that no cigarette remains in the conveyor to dry out. When the device is operated, the buyer gets a cigarette taken directly from the humidifying conditions of the hopper. The cigarette is not maintained in contact with the igniter for any appreciable length of time to have the heat dry out the tobacco of the cigarette since the cigarette pauses in alignment with the igniter only long enough to be ignited.

Only the best embodiment of my invention of which I am at present informed has been shown but it is shown in an illustrative sense and not a limiting one for obviously many modifications are possible in construction and arrangement with-

out departing from the spirit and scope of the appended claims.

For instance, whereas I have described my dispenser as coin controlled, I may substitute for a coin in the coin-chute as an initiator for closing 5 the auxiliary circuit, a push-button or any other arrangement which will momentarily close the auxiliary circuit.

Where the dispensers are used to sell their cigarettes, the coin control will be used but if the dispensers should be used in a home or club where the sale of the cigarettes is not involved in their dispensing, the push button or non-coin control will be used to initiate the dispensing operation.

I claim:

1. A cigarette dispensing machine having a cigarette container, a cigarette dispensing tray, a cigarette discharging conveyance for carrying a cigarette from the container to the tray, an igniter between the container and the tray, an electrical circuit, a motor therein connected to motivate the conveyance characterized by the fact that the motor continuously operates when its circuit is closed and by mechanism for causing the conveyance driven from the motor to pause automatically when its cigarette comes into register with the igniter and after a pause to start on its way again.

2. Dispensing apparatus according to claim 1 in which said conveyance comprises a rotatably mounted grooved drum, and wherein said mechanism for causing the conveyance driven from the motor to pause automatically when its cigarette comes into register with the igniter and after a pause to start on its way again comprises 30 a train of elements driven by the motor extending from the motor to the drum which includes a pair of coacting gears one of which is multi-lated.

3. A dispenser for lighted cigarettes having a 40 reservoir for maintaining therein cigarettes to be dispensed; a throat passage leading therefrom through which cigarettes can pass from the reservoir by gravity and of a size that it is substantially closed by the presence therein of one 45 cigarette; a sloping bottom portion being included in the reservoir inclined toward the throat which in preferred form is vertically disposed; movable means associated with said reservoir for conveying cigarettes upwardly along at least a part of 50 the sloping bottom away from the throat for setting up a mass motion movement of the cigarettes in the hopper to assure the orderly feed of cigarettes to the throat while creating a minimum of tobacco crumbs from the cigarettes; a cigarette igniter element in an operating circuit; a conveyor for containing and conducting one cigarette at a time from the throat past the igniter to dispensing discharge from the conveyor; motor driven apparatus for operating said movable 60 means and said conveyor; means for rendering the motor operable; and automatic means for stopping the motor and its operated parts after a lighted cigarette has been dispensed, in a relationship that no cigarette is left in the conveyor 65 upon the cessation of its movement.

4. A dispenser for lighted cigarettes having a reservoir for maintaining therein cigarettes to be dispensed; a throat passage leading therefrom through which cigarettes can pass from the reservoir by gravity and of a size that it is substantially closed by the presence therein of one cigarette; a cigarette igniter element in an operating circuit; a conveyor for containing and conducting one cigarette at a time from the throat past 70

- the igniter to dispensing discharge from the conveyor; motor driven apparatus for operating said conveyor; means for rendering the motor operable; and automatic means for stopping the motor and its operated parts after a lighted cigarette has been dispensed, in a relationship that no cigarette is left in the conveyor upon the cessation of its movement.
5. A dispenser for lighted cigarettes having a reservoir for maintaining therein cigarettes to be dispensed; a passage leading therefrom through which cigarettes can pass from the reservoir one

at a time; a cigarette igniter element in an operating circuit; a conveyor for conducting one cigarette at a time from the passage past the igniter to dispensing discharge from the conveyor; motor driven apparatus for operating said conveyor; means for rendering the motor operable; and automatic means for stopping the motor and its operated parts after a lighted cigarette has been dispensed, in a relationship that no cigarette is fed into lighting position upon 10 cessation of the movement of the conveyor.

DONALD BRUCE LANE.
